UNITED STATES PATENT OFFICE.

ARTHUR W. BOWSER, OF CELINA, OHIO.

WASHING-MACHINE.

1,333,153.

Specification of Letters Patent.

Patented Mar. 9, 1920.

Application filed May 16, 1919. Serial No. 297,476.

To all whom it may concern:

Be it known that I, ARTHUR W. BOWSER, a citizen of the United States, residing at Celina, in the county of Mercer and State of Ohio, have invented certain new and useful Improvements in Washing-Machines; and I do hereby declare the following to be a full, clear, and exact description of the invention, such as will enable others skilled 10 in the art to which it appertains to make and use the same.

The present invention relates to washing machines, and aims to provide a novel and improved construction of that character 15 which is simple and inexpensive as well as being thoroughly practical and efficient in use.

The invention has for its object the provision of a sheet metal tub provided with an 20 interior frame to which the bottom and walls of the tub are secured, to render the tub rigid, and to also provide means against which the clothes rub to facilitate the washing and cleaning thereof when the agitator 25 is operated.

With the foregoing and other objects in view, which will be apparent as the description proceeds, the invention resides in the construction and arrangement of parts hereinafter described and claimed, it being understood that changes can be made within the scope of what is claimed without departing 30 from the spirit of the invention.

The invention is illustrated in the accompanying drawing, wherein—

Figure 1 is a horizontal section of the tub above the agitator.

Fig. 2 is a vertical section taken on the line 2—2 of Fig. 1.

40 The tub 1 is of sheet metal and is of rectangular form. A frame is provided in the tub, comprising two pairs of bars or cleats 2 extending in directions at right angles with one another parallel to the sides of the 45 tub, and said bars 2 cross one another near the corners of the tub and are located near the respective sides, as clearly seen in Fig. 1. Vertical bars or cleats 3 are secured to the ends of the horizontal bottom bars 2 and 50 extend along and are secured to the sides of the tub upon the interior thereof. Top boards or pieces 4 are secured on the upper

ends of the bars 3 around the rim of the tub and provide a top having a central opening in which a cover or door 5 is provided, being hinged, as at 6, to one bar 4. Pieces 7 are secured to the under sides of the boards 4 and provide a seat for the cover 5, and a suitable catch 8 can be used for holding the cover closed. A wringer support 9 is preferably carried by the board 4 opposite to the hinge 6 for convenience in wringing the clothes.

The frame thus provided within the tub serves to render the tub substantial and rigid, and also provides means for the clothes to rub against in order to facilitate in loosening the dirt, when the agitator is operated. The vertical bars 3 are located near the corners, where the bars 2 cross, and this arrangement of the bars 2 and 3 will effectively serve the intended purpose.

The agitator is carried by a vertical rock shaft 10 extending centrally through the cover 5, and the agitator includes a hub 11 secured to the lower end of the shaft 10 and having radial paddles 12 fastened by clips 13 to the hub, although a metal cast agitator can be used instead of one built up as illustrated. The shaft 10 has a collar 14 to rest 80 upon the cover for supporting the dasher in its lowermost position, and the upper end of the shaft has a radial handle 15 for convenience in rocking the agitator, which in resting on the clothes will agitate them, by 85 moving the clothes back and forth against the bottom and side bars or cleats 2 and 3, respectively.

The tub can be placed on a stove, bench, table or other support, or can be provided 90 with suitable legs for supporting it above the floor.

Having thus described the invention, what is claimed as new is:—

1. A washing machine embodying a tub, bars secured on the bottom thereof and crossing one another at a plurality of points near the sides of the tub, vertical bars secured to the aforesaid bars and the sides of the tub, said bars providing a frame on 95 the interior of the tub, and an agitator to work within the tub.

2. A washing machine embodying a tub of angular form, bars secured on the bottom

thereof adjacent to the sides and crossing one another near the corners of the tub, vertical bars secured to the ends of the aforesaid bars and to the sides of the tub near the corners, and an agitator to work within the tub centrally thereof.

5 In testimony whereof I have signed my

name to this specification in the presence of two subscribing witnesses.

ARTHUR W. BOWSER.
